(57) **CLAIM**

The ornamental design for a display screen or portion thereof with animated graphical user interface for display login and browsing information as shown and described.

DESCRIPTION

1. Display screen or portion thereof with animated graphical user interface for display login and browsing information

1.1 : Front

1.2 : Front

1.3 : Front

1.4 : Front

The appearance of the animated graphical user interface sequentially transitions between the images shown in FIGS.

1.1-1.4. The process or period in which one image transitions to another image forms no part of the claimed design. Texts including English characters “Sign up” and “Log in”, and texts including rows of Xs do not form part of the claimed design. The close icon “x” within a circle in the upper right corner of FIG. 1.3 and FIG. 1.4 forms a part of the claimed design.

Broken lines in FIGS. 1.1 to 1.4 illustrate the display screen or portion thereof.
